UNITED STATES PATENT OFFICE.

CHARLES ERNEST SCHWARTZ, OF STANFORD UNIVERSITY, CALIFORNIA.

DESIGN FOR A CLIPPING-HOLDER.

SPECIFICATION forming part of Design No. 29,519, dated October 18, 1898.

Application filed September 21, 1898. Serial No. 691,559. Term of patent 14 years.

To all whom it may concern:

Be it known that I, CHARLES ERNEST SCHWARTZ, of Stanford University, in the county of Santa Clara and State of California, have invented and produced a new and original Design for a Clipping-Holder, of which the following is a full, clear, and exact description.

Reference is to be had to the accompanying drawing, forming a part of this specification, in which the figure is a perspective view of a clipping-holder showing my design.

The design consists of the covers A and B, of which the cover A is continued at its up-

per end into a flap C, one side of which appears with a superimposed longitudinal strip D, having a flange D' extending at an angle to the strip D and the flap C.

The leading feature of my design consists of the connected covers and the flap extending from one end of one of the covers.

I claim—

The design for a clipping-holder, herein shown and described.

CHARLES ERNEST SCHWARTZ.
